DESIGN FOR A CLOTHES AND SHOE CABINET
OR THE LIKE

Augusta P. Finkelstein, Woonsocket, R. I.

Application March 25, 1947, Serial No. 137,877

Term of patent 7 years

(Cl. D33—8)

To all whom it may concern:

Be it known that I, Augusta P. Finkelstein, a citizen of the United States, residing in Woonsocket, in the county of Providence and State of Rhode Island, have invented a new, original, and ornamental Design for a Clothes and Shoe Cabinet or the like, of which the following is a specification, reference being had to the accompanying drawing, forming a part thereof, in which Fig. 1 is a perspective view of the cabinet looking down and at two adjacent sides, and Fig. 2 is a side elevation of the left hand side of Fig. 1. The other two sides are similar to the side of Fig. 2.

I claim:

The ornamental design for a clothes and shoe cabinet or the like, as shown and described.

AUGUSTA P. FINKELSTEIN.
